CLAIM

The ornamental design for a blender jar, as shown and described.

DESCRIPTION

FIG. 1 is a front perspective view of a blender jar of the present disclosure;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The broken lines in the drawings depict portions of the blender jar that form no part of the claimed design.
